UNITED STATES PATENT OFFICE.

DAVID CARLAW, OF GLASGOW, SCOTLAND.

CUTTING-MACHINE.

SPECIFICATION forming part of Letters Patent No. 662,186, dated November 20, 1900.

Application filed December 28, 1897. Serial No. 664,004. (No model.)

To all whom it may concern:

Be it known that I, DAVID CARLAW, a subject of the Queen of Great Britain and Ireland, and a resident of Glasgow, Scotland, have 5 invented certain new and useful Improvements in Cutters, (for which I have obtained a patent in Great Britain, No. 23,048, bearing date October 17, 1896,) of which the following is a specification.

10 This invention has reference to improvements in the cutting and delivery mechanism of printing-machines where an intermittent motion is employed.

In the accompanying drawings, Figures 1 15 and 2 are an elevation and plan view, respectively, of the delivery end of a printing-machine to which my improvements are applied.

In printing tickets in this machine they are 20 carried on endless tapes D, after having been cut off in rows of, say, fifty from the printed web z, and they are delivered at the end of the traverse to the flier G to be stacked up.

A knife consisting of a steel bar E set at a 25 slight inclination is mounted on a transverse web E' at one end of an oscillating frame E², which is in turn mounted in brackets E⁴, cast in one with a frame E³. This latter is adjustable by slotted lugs and pinching-pins E⁵.

30 in the side rails of the machine. The bar-knife E receives an up-and-down motion over a corresponding fixed bar e in close proximity to the traveling band, so that when the rows of tickets are cut off they drop onto the 35 traveling bands D. Intermittent motion is given to these traveling bands by a connecting-rod X, having a crank connection to the driving-shaft e⁵ at one end and operating a pawl x, engaging the ratchet-wheel x', set 40 cured to the shaft of the drum D', around which the bands D pass. The oscillating frame E² receives its downward-travel motion, by rods e' on each side of the frame with slotted ends e² and cams e³ and antifriction-pul-

ley e⁴, from a rotating shaft e⁵ at bottom of 45 machine. The recoil action of spiral springs f, attached to an overhead frame f', fixed to machine, will give the oscillating frame E² the return upward motion after each action of cutting the strips of tickets. 50

A metal band-flier G is fitted near the delivery end of tapes D, which carry the strips of tickets. The ends of this band G are secured to levers G', mounted on a transverse spindle G², and one of these levers is connected by a rod G³ to be actuated from a cam similar to those used for actuating the knife-bar, and a spring G⁴ is provided to return the band-flier to its initial position. By this means the band-flier G gets an intermittent 55 tilting motion to receive each strip or row of tickets as it is delivered by the band D and throw same over on its edge, the several strips being delivered in parallel line, so that they can be manipulated at a glance. 60

I claim as my invention—

1. In mechanism for cutting and stacking strips of tickets, &c., the combination of an oscillating knife to cut the strips, with a flier and bands to receive the cut strips from the 70 knife, and deliver them to the flier, and means for intermittently operating the knife, bands and flier, substantially as described.

2. In mechanism for cutting and stacking strips of tickets, &c., the combination of an 75 oscillating knife to cut the strips, with a flier and bands to receive the cut strips from the knife and deliver them to the flier, and means for intermittently operating the knife, bands and flier, all from one continuously-driven 80 shaft, substantially as described.

In testimony whereof I have signed my name to this specification in the presence of two subscribing witnesses.

DAVID CARLAW.
